Primary Examiner — Omeed Agilee*Assistant Examiner* — David Truong(74) Attorney, Agent, or Firm — Blank Rome LLP; Tara L. Marcus(57) CLAIM

The ornamental design for a cigarette package as shown and described.

DESCRIPTION

FIG. 1 is a front perspective view of a cigarette package showing our new design;

FIG. 2 is a front elevation view thereof, with a rear elevation view being a mirror image thereof;

FIG. 3 is a top plan view thereof;

FIG. 4 is a bottom plan view thereof; and,

FIG. 5 is a left side elevation view thereof, with the right side elevation view being a mirror image thereof.

The broken lines in the drawings depict portions of the cigarette package that form no part of the claimed design.

1 Claim, 3 Drawing Sheets(56)
